UNITED STATES PATENT OFFICE

164,353

WIND STATIC DISCHARGER FOR AN
ANTENNA

Franklin C. Brewster, Franklin Park, Ill., assignor
to Motorola, Inc., Chicago, Ill., a corporation
of Illinois

Application March 10, 1951, Serial No. 14,459

Term of patent 3½ years

(Cl. D26—14)

To all whom it may concern:

Be it known, that I, Franklin C. Brewster, residing in the village of Franklin Park, county of Cook, State of Illinois, have invented a new, original, and ornamental Design for a Wind Static Discharger for an Antenna, of which the following is a specification, reference being had to the accompanying drawing, forming a part thereof, in which:

Fig. 1 is a perspective view of a wind static discharger for an antenna showing my new design;

Fig. 2 is a side elevation view of the wind static discharger;

Fig. 3 is a front elevation view of the wind static discharger; and

Fig. 4 is a top plan view of the wind static discharger.

The characteristic features of my new design are shown in solid lines in the drawings, the

dotted lines shown in Fig. 1 being for illustrative purposes only, both as to type of mounting and placement thereof.

I claim:

The ornamental design for a wind static discharger for an antenna, substantially as shown and described.

FRANKLIN C. BREWSTER.
